P. F. SCHECHER,
VULCANIZER.
APPLICATION FILED SEPT. 12, 1921.

UNITED STATES PATENT OFFICE.

PETER F. SCHECHER, OF ST. MARYS, KANSAS.

VULCANIZER.

1,411,225.

Specification of Letters Patent. Patented Mar. 28, 1922.

Application filed September 12, 1921. Serial No. 500,131.

To all whom it may concern:

Be it known that I, PETER F. SCHECHER, a citizen of the United States, residing at St. Marys, in the county of Pottawatomie and 5 State of Kansas, have invented new and useful Improvements in Vulcanizers, of which the following is a specification.

This invention relates to vulcanizers such as are used for repairing automobile tire 10 tubes and has for its object the provision of an improvement in the vulcanizer of the type known as the Gwynn-Bacon tube vulcanizer.

This type of vulcanizer is well known and 15 includes a base portion from which rise a plurality of L-shaped arms which are provided at their extremities with clamping screws for holding the tube onto the base. It is well known to users of this device that 20 the construction is faulty inasmuch as the mounting of the arms or supports is weak which results in giving or yielding of the arms when the clamping screws are turned down tight. It is with the above mentioned 25 defects in view that the present invention has been designed and which has for its object the provision of means whereby the already existing arms of this type of vulcanizer may be strengthened and which also 30 has for an object the provision of arms of an improved pattern which are so formed that they will brace themselves.

Another object is the provision of an improved clamping screw which is more easily 35 turned and by means of which greater pressure may be inserted than is possible with the ordinary screw.

An additional object is the provision of 40 means of this character which will be simple and inexpensive in manufacture, highly efficient in use, durable in service, and a general improvement in the art.

With the above and other objects and advantages in view, the invention consists in 45 the details of construction to be hereinafter more fully described and claimed and illustrated in the accompanying drawings in which

Figure 1 is a side elevation of a vulcanizer 50 of the Gwynn-Bacon type showing my bracing means applied to an arm thereof,

Figure 2 is a perspective view of the brace member detached,

Figure 3 is an end elevation of a vulcan-

izer of this type equipped with one of my 55 arms, and

Figure 4 is a perspective view of the improved arm alone.

Referring more particularly to the drawings, the letter A designates the base portion 60 of a Gwynn-Bacon vulcanizer, this base portion being adapted to be heated by the usual means, not shown. At the upper edge of the base is formed a rearwardly extending flange B which supports the usual arms C, 65 only one being shown in the present instance. Each arm is of metal and includes a vertical portion D terminating in a threaded extension E passing through the flange B and carrying a clamping nut F. 70 Each arm further includes a laterally extending or horizontal portion G, near the end of which is provided a threaded hole through which is passed a clamping screw which ordinarily is of the wing type. 75

In carrying out the form of the invention disclosed in Figures 1 and 2, I provide a brace for this supporting arm, this brace being formed of sheet metal of suitable gauge bent to form a cylindrical sleeve 10 of a size 80 to encircle the shank D. Formed on the edge of this sleeve are triangular ears 11 through which pass clamping bolts 12. It is preferable to provide a plate 13 which is disposed upon the top of the base A and 85 which extends rearwardly beyond the flange B with its rearmost edge preferably down-turned, as indicated at 14. This plate is of course apertured for the passage of the threaded extensions E of the arms C and it 90 will be apparent that the plate will be held in position by the arms C. In applying my bracing device the sleeve portion 10 thereof is disposed in encircling relation to the shank D with the lower edge of the ears 11 95 bearing upon the top of the plate 13. The bolts 12 are of course tightened to prevent the sleeve from rotating upon the shank D and to hold the parts firmly in position. Owing to the provision of the triangular 100 ears it will be apparent that efficient bracing means is provided which will prevent yielding or giving of the arms under any conditions.

Another feature of my invention is the 105 use of a clamping screw 15 of crank shape instead of the usual wing screw, and it will be apparent that this crank-shaped screw is

more easily operable as a greater leverage may be obtained.

Referring to the form of the device shown in Figures 3 and 4, it will be seen that I have provided a modified form of arm to take the place of the ordinary arm. In these figures the numeral 16 designates the arm which is formed L-shaped to provide a horizontal portion 17 for the passage of the 10 clamping screw and to provide a vertical portion 18 from which extends a reduced threaded extension 19 corresponding to the extension E of the first described form. The vertical portion 18 of the arm is formed 15 with an extension 20 which extends to the edge of the plate 13 and which constitutes an effective brace, as will be obvious.

It is of course to be understood that the 20 operation of my device is identically the same as that of the well known vulcanizer of the type mentioned, my invention relating merely to the structural details whereby to increase the strength and consequently the durability of the vulcanizer.

25 While I have shown and described the

preferred embodiment of my invention, it is of course to be understood that I reserve the right to make such changes in the form, construction and arrangement of parts as will not depart from the spirit of the invention or the scope of the subjoined claim.

Having thus described my invention, I claim:

In a vulcanizer including a base and a plurality of substantially L-shaped arms 35 rising therefrom and formed with reduced threaded extensions passing through a portion of the base and carrying clamping nuts; bracing means comprising a plate disposed upon the top of the base and extending considerably beyond the rear edge thereof and formed with holes for the passage of the reduced extensions, and a sleeve adapted to be clamped about the vertical portion of each arm and formed with triangular ears 40 engaging upon the top of said plate and extending in the opposite direction to the horizontal portion of the arm.

In testimony whereof I affix my signature.

PETER F. SCHECHER.
